UNITED STATES PATENT OFFICE.

WILLIAM H. MYERS, OF BROOKLYN, NEW YORK.

COMBINATION TOP FOR GAS RANGES.

Application filed November 17, 1927. Serial No. 233,904.

My invention relates to combination open and closed tops for gas ranges.

Heretofore gas ranges have been made with open tops or kettle rests to give better ventilation and combustion and quicker heating, or with closed tops, which, while not so efficient as to ventilation, combustion and heating, permit the whole top to be heated by one or less than the whole number of, usually 10 four, burners.

Gas ranges have also been proposed with interchangeable open and closed tops, and with circular kettle openings to be closed by circular lids.

15 My invention consists of a combination open and closed top having the advantages in both adjustments of the open top in respect to perfect ventilation and combustion and effective heating, and comprises as an 20 entirety, in its present preferred embodiment, a range top having burner openings and fingers serving as open kettle rests projecting by preference radially into said openings, and removable lids to cover said openings and 25 serve as closed kettle rests, said lids having radial outward projections to fill in the spaces between the inwardly projecting fingers or open kettle rests.

I may make the corresponding edges of the 30 fixed inward and movable outward projections correspondingly beveled downwardly and inwardly but spaced to assist ventilation, combustion and heating, or I may make the corresponding beveled edges close fitting but 35 scalloped or indented to assist ventilation, combustion and heating, as hereinafter more fully described.

In order that my invention may be fully understood, I shall first describe in detail 40 the mode in which I at present prefer to carry the invention into practice and then particularly point out the invention in the claim.

Reference is to be had to the accompanying 45 drawings forming part of this application, in which like parts are designated by the same numbers in all the figures.

Figure 1 is a plan view of a combination open and closed top for a gas range, embodying my invention.

Figure 2 is a cross sectional view of the same on the line 2—2, Figure 1.

Figure 3 is a plan view showing a modified form of my invention.

55 In the embodiment of my invention shown in Figures 1 and 2, number 4 designates the

solid top of a gas range, which may have small ventilating openings therein as shown.

I form the openings 5 in the solid top over each burner with inwardly projecting, preferably radial, fingers 6, cast integrally with the solid top to serve as open kettle rests and I may make said openings 5 separate or connected as desired. Each fingered opening 5, is provided with a removable lid 65 7 cast integrally with outward projections 8 to fill and cover the radial spaces between the inward projections 6, and thus serve as a closed kettle rest.

To support the star-like lid 7 thus formed 70 flush in its corresponding opening 5, I prefer to cast integrally with the solid top 4, across and beneath the outer ends of some of the radial spaces between the fingers 6, shelves 9 on which the outer ends of the lid 75 projections 8 rest.

To provide for effective ventilation, combustion and heating when the closed top is used, I prefer to space slightly the corresponding edges of the fingers 6 and lid projections or fillers 8, and bevel the same inwardly and downwardly so that the beveled edges 10 of the lid will cover but not close the intervening spaces.

I may also to the same end as illustrated 85 in Figure 3, scallop, indent or serrate the edges of the fingers and top at intervals around the fillers 8 and close the beveled joints between the fingers and fillers, so that the expansion of the top and lid over the 90 lighted burner will cause the lid to be lifted and rise above the solid top, and thus open without uncovering the spaces at the scallops, indentations or serrations 11.

The lids 7 may of course be joined in pairs 95 or otherwise according as the corresponding openings 5 are separate or connected, and each lid is provided with the usual socket 12 to receive the lid lifter.

It is evident that the specific embodiment 100 of my invention herein illustrated may be greatly varied in detail without departing from the boundaries of my invention as defined by the following claim.

I claim as my invention:

A combination open and closed top for gas ranges comprising an open top having a large central gas burner opening, corresponding to the central part of the gas burner, from which radiate openings corresponding to the radiating parts of the gas burner, leaving inwardly projecting kettle rests between the ra 105 110

dial openings, and a removable lid having a solid central portion substantially to fit and cover the central opening and solid portions radiating from the central portion substantially to fit and cover the respective radial openings in the open top the edges of the radiating portions of the lid being slightly

spaced from the corresponding edges of the radial openings of the open top to permit the passage of the air and gases through the spaces thus formed.

In testimony whereof I affix my signature.

WILLIAM H. MYERS.
